UNITED STATES PATENT OFFICE.

ARTHUR MOORE, OF TORONTO, CANADA.

GRAIN SCOURER AND CLEANER.

SPECIFICATION forming part of Letters Patent No. 443,372, dated December 23, 1890.

Application filed February 20, 1890. Renewed October 30, 1890. Serial No. 369,790. (No model.)

To all whom it may concern:

Be it known that I, ARTHUR MOORE, merchant miller, of the city of Toronto, in the county of York, in the Province of Ontario,

5 Canada, have invented certain new and useful Improvements in Grain Scourers and Cleaners, of which the following is a specification.

10 My invention relates to certain improvements made by me upon a grain scourer and cleaner patented to me by the Dominion of Canada on the 16th day of July, 1889, under No. 31,718, and by the United States of America on the 16th day of July, 1889, under No. 406,931, the object of the improvements being 15 to insure a more thorough cleansing of the wheat by a more perfect arrangement of the air legs and chambers, by which the circulation of the air is improved and is caused to act more thoroughly upon the grain in passing through the machine.

20 Figure 1 is a perspective sectional view of the machine, showing the inlet and outlet grain-spouts with the air-legs acting upon them. Fig. 2 is a similar view of the machine 25 made at right angles to the view shown in Fig. 1, the perforated cylinder being removed.

In the drawings, A represents a perforated cylinder placed within an air-chamber B. The top of the cylinder A is closed by a cover C. 30 A conveyer D is fixed to a small perforated pipe or tube E, connected to the shaft E', on the top of which the fan F is secured. The chamber B communicates with the interior of the casing of the fan F, which is made to act 35 as an exhaust-fan to draw the air from the said chamber B and discharge it into the blast-chamber G. An imperforate cylinder H is placed within the perforated cylinder A and fixed by the arms I to the shaft E', with 40 which it revolves. Around the outer circumference of the imperforate cylinder H, I fix a series of blades a, shaped to correspond with the blades of the conveyer D, in fact constituting a portion of the said conveyer D. The 45 base of the cylinder H rests upon the perforated bed-plate J, which has a flange b formed on it to fit inside the cylinder H to prevent the wheat escaping. The flange b surrounds a hole made in the bed-plate J, which bed-plate is supported a little above the bottom 50 d of the air-chamber. Air-legs K (see Fig. 2) connect the space between the bottom d and

bed-plate J and the blast-chamber G. The bottom of the cylinder E is left open, so as to communicate with the interior of the cylinder H.

When the fan F is put in operation, it exhausts the air in the chamber B, discharging it in the blast-chamber G, and as this latter chamber is connected to the bottom of the chamber B by the air-legs K a constant upward circulation is produced in the chamber B. The upward current produced in the said chamber acts through the perforations in the cylinder A, carrying through the said perforations dust and wheat scourings produced by the action of the machine. The screenings-chamber L being connected to the air-chamber B by the opening M, an upward current is produced in the screenings-chamber L, similar 65 to the current in the chamber B. An air-leg N, provided with a regulating-valve n, communicates, as shown, with the blast-chamber G and with the bottom of the grain-leg O, which grain-leg is connected, as shown, with the 70 screenings-chamber L. Consequently the air which is forced down through the air-leg N into the bottom of the grain-leg O passes up the said grain-leg into the screenings-chamber L, from which it finds its way back into 75 the chamber B, as before described. In this way a constant upward current is maintained in the grain-leg O and upper part of screenings-chamber L, as well as in the air-chamber B. The grain which enters the machine 80 through the grain-spout P falls upon the valve Q, spreading over the face of the said valve, which is set to permit a thin stream of the grain to fall upon the slanting shelf R, which scatters the grain as it falls to the bottom of 85 the grain-leg O, which conveys it, as indicated, into the bottom of the perforated cylinder A. The upward current of air already described in the grain-leg O carries the dust and other light particles of foreign matter to the top of 90 the grain-leg O, where it comes in contact with the deflecting-plate S, which projects into the screenings-chamber L below the bottom of the opening, so as to cause a slight downward draft at this point in the chamber 95 L, directing the screenings toward the bottom of the said chamber, from which it is withdrawn through the spout T, the dust passing 100 on upward to the fan F. The grain which

enters the bottom of the perforated cylinder A is immediately acted upon by the blades α , which elevate the said grain. The centrifugal force produced by the revolving of the 5 conveyer D holds the grain in substantially the same thickness all the way around the case up to the top of the conveyer, where it is discharged out of the spout U. A valve V is placed in the end of the spout U at the 10 point where it opens into the chamber W, so as to regulate the discharge of the grain from the spout U on the shelf V', which scatters the grain as it falls into the said chamber W, which has an opening at its bottom provided 15 with a regulating-valve X. An air-passage-way Y connects at one end with the blast-chamber G and at its other end with the chamber W, so that a current of air is forced down through the passage-way Y into the said 20 chamber W. A screenings-chamber Z is connected to the chamber W by an opening located at or near the top of the said chamber W. Consequently the air which is forced into the chamber W passes into the chamber Z and 25 up the said chamber back into the chamber B through the opening Z'. Owing to this arrangement of air-passages the grain falling from the valve V is acted upon by the current of air passing up the chamber W. The said 30 current of air carrying any dust or light foreign matter from the grain, conveys it into the screenings-chamber Z, on entering which it comes in contact with the deflecting-plate X', which precipitates the screenings toward the 35 bottom of the chamber Z, from which it is removed through the opening made in the bottom of the said chamber, the dust passing upward to the fan F through the opening Z'. The deflecting-plate X', being carried down 40 the chamber Z below the opening in the said chamber to the chamber W, causes the downward current of air at this point, precipitating the screenings, as before mentioned.

Owing to the thin layer of grain in motion 45 against the wall of the perforated cylinder A, the current of air will pass freely through it, carrying away every particle of dust which may have been released from the grain, leaving little or no work to be done by the current of air maintained in the discharging-chamber W. A valve Y' is placed in the air-passage Y, so that the strength of the blast in the said air-passage may be regulated.

A skirt G' extends from the base of the 50 fan-easing to a point below the opening of the air-legs or passage-ways leading from the blast-chamber G to the interior of the machine. This skirt effectually protects the openings of the said air-legs or passage-ways

from the dust which is blown into the blast-chamber by the action of the fan. The said dust sinks to the bottom of the blast-chamber, from which it is withdrawn through openings made in the bottom of the blast-chamber for that purpose.

What I claim as my invention is—

1. In a grain scouring and cleaning machine, the combination of the perforated cylinder A, having one end closed, the air-chamber B, surrounding and communicating with said cylinder, the shaft E', arranged in the cylinder A, the cylinder II on said shaft, the conveyer D on shaft E', the fan F on the shaft E', the blast-chamber G, and the air-legs K, connecting or forming communication between the air-chamber B and blast-chamber G.

2. In a grain scouring and cleaning machine, the combination of the perforated cylinder A, the air-chamber B, surrounding the same, the air-legs K, communicating with said air-chamber, the shaft E', revolving in the cylinder and carrying the conveyer D, the cylinder II, fitting in the cylinder A and revolving therein, and the fan F, all adapted to operate as described.

3. In a grain scouring and cleaning machine, the combination of cylinder A, air-chamber B, fan F, blast-chamber G, air-leg N, grain-leg O, and screenings-chamber I, communicating with air-chamber B.

4. In a grain scouring and cleaning machine, the combination of cylinder A, conveyer D, fan F, air-chamber B, and screenings-chamber I, as described.

5. In a grain scouring and cleaning machine, the combination of cylinder A, conveyer D, fan F, blast-chamber G, air-chamber B, air-leg N, grain-leg O, and screenings-chamber I, as described.

6. In a grain scouring and cleaning machine, the combination of cylinder A, conveyer D, fan F, spout U, chamber W, air-passage way I, and blast-chamber G, as described.

7. In a grain scouring and cleaning machine, the combination of cylinder A, conveyer D, fan F, chamber W, blast-chamber G, and chamber Z, as described.

8. In a grain scouring and cleaning machine, the combination of cylinder A, conveyer D, fan F, blast-chamber G, air-passage way Y, chamber W, spout U, valve V, and chamber Z, as described.

Toronto, February 1, 1890.

ARTHUR MOORE.
